US00D896209S

(12) **United States Design Patent** (10) **Patent No.:** **US D896,209 S**
Jannard et al. (45) **Date of Patent:** **** Sep. 15, 2020**

(54) **ELECTRONIC DEVICE**

(71) Applicant: **RED HYDROGEN LLC**, Solana Beach, CA (US)

(72) Inventors: **James H. Jannard**, Las Vegas, NV (US); **Peter Jarred Land**, Los Angeles, CA (US); **Matthew Tremblay**, Laguan Beach, CA (US)

(73) Assignee: **RED.COM, LLC**, Irvine, CA (US)

(**) Term: **15 Years**

(21) Appl. No.: **29/697,384**

(22) Filed: **Jul. 8, 2019**

(57) **CLAIM**

The ornamental design for an electronic device, as shown and described.

DESCRIPTION

FIG. 1 is a front perspective view of the electronic device of the present invention;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines show portions of the electronic device that form no part of the claimed design.

1 Claim, 5 Drawing Sheets
